UNITED STATES PATENT OFFICE.

AMAND CARL MARIA PRÜCKER, OF HANOVER, GERMANY, ASSIGNOR TO THE SIEMENS & HALSKE ELECTRIC COMPANY OF AMERICA, OF CHICAGO, ILLINOIS.

INCANDESCENT-LAMP BASE AND SOCKET.

SPECIFICATION forming part of Letters Patent No. 623,623, dated April 25, 1899.

Application filed August 31, 1898. Serial No. 689,924. (No model.)

To all whom it may concern:

Be it known that I, AMAND CARL MARIA PRÜCKER, a subject of the Emperor of Austria-Hungary, residing at Hanover, Germany, have invented a certain new and useful Improvement in Incandescent-Lamp Bases and Sockets, (Case No. 158,) of which the following is a full, clear, concise, and exact description.

10 My invention relates to improvements in incandescent-lamp base and socket adapted to be inserted therein, and has for its object the provision of means for preventing the accidental loosening of the base when within 15 said socket and for insuring continuous electrical contact between the base and the contact parts of the socket.

Briefly described, my invention contemplates the provision in a contact-making 20 socket or device of a spring-like tongue adapted to engage serrations or notches provided upon the contact-making base when the same is inserted within the socket, whereby the base is withheld from accidental release from 25 its position within the socket and the electrical continuity of the parts is insured.

I will describe my invention more at length by reference to the accompanying drawings, wherein—

30 Figure 1 is a sectional view of a contact-making socket and base. Fig. 2 is a plan view of the same. Fig. 3 illustrates my invention applied to an Edison lamp socket and base, and Fig. 4 is a plan view thereof.

35 The same letter of reference is used to designate corresponding parts in each of the several figures of the drawings.

Upon the insulating base-plate *G* are mounted the terminal screws *a* *b*, the former being 40 connected with a forked plate *c*, the extremities of which are bent upward and form spring-like tongues *g*, diametrically disposed upon either side of the central contact-screw *d*. This screw is connected with the terminal screw *b* by means of a bar extending between the said parts in a recess provided in the insulating-base *G*. The lamp-base *E* is provided with a centrally-disposed threaded sleeve *e*, which is adapted to screw upon part 45 *d*, the said sleeve forming one terminal con-

tact part for the lamp, while the external sleeve *f*, provided upon the base, forms the second contact part. The sleeve *f* is serrated or notched at its lower end, the notches therein being adapted to be engaged by the spring-tongues *g* when the lamp-base is screwed into position to secure electrical connection with the coacting contact parts. It will be at once understood that when the base *E* is thus screwed down upon part *d* the serrations 55 provided in its outer sleeve will be engaged by the spring-like tongues carried by plate *c*, and thus the said base will be prevented from being accidentally unscrewed from its contact-making device. The base, however, 60 may be readily removed, since the springs *g* will be depressed, permitting the rotation of the base in either direction when the same is turned by hand. In addition to preventing the accidental release of the base the springs 65 *g* secure the firm engagement of the several contact parts.

Figs. 3 and 4 illustrate the application of my invention to an Edison lamp socket and base wherein the well-known threaded exterior sleeve is employed. The terminal binding-screws *a'* and *b'* are respectively connected with the contact-plates *c'* and *c*, the former in turn being connected with the threaded sleeve of the lamp-socket, while the latter is 80 provided with an upperly-projecting part *g*, adapted to engage the central contact part of the lamp-base. Contact-plate *c* is centrally mounted in the lamp-socket by means of the screw *d'*. The coacting central contact-piece 85 *f*, provided upon the lamp-base *E*, is peripherally serrated or notched, which notches are adapted to be engaged by the spring-tongue *g* when the base *E* is screwed within the socket, thereby maintaining the lamp-base in position against accidental dislodgment.

It is obvious that my invention may be applied to other forms of contact-making bases and sockets than those herein specifically shown and described in illustration of my 95 said invention, and I do not desire to be understood as limiting the same to the precise embodiment herein shown and described.

Having set forth types of apparatus exemplifying my improvement, what I claim as 100

new, and desire to secure by these Letters Patent, is—

An improved Edison socket contact device comprising a threaded conducting-socket, a terminal part at the extremity of said socket having a spiral, upwardly-extending tongue *g*, an exteriorly-threaded base *E* and a serrated contact part *f* provided on said base with which the free end of tongue *g* is adapted to engage and hold the said base in the socket

when the same is screwed therein under compression of said spiral, substantially as described.

In witness whereof I hereunto subscribe my name this 13th day of August, A. D. 1898.

AMAND CARL MARIA PRÜCKER.
